UNITED STATES PATENT OFFICE.

ALBERT PETERSON, OF DETROIT, MICHIGAN.

COMBINED CORNER-PROTECTOR AND LOCK FOR BAGS OR SATCHELS.

SPECIFICATION forming part of Letters Patent No. 372,762, dated November 8, 1887.

Application filed August 1, 1887. Serial No. 245,789. (No model.)

To all whom it may concern:

Be it known that I, ALBERT PETERSON, a citizen of the United States, residing at Detroit, in the county of Wayne and State of Michigan, have invented certain new and useful Improvements in Combined Corner-Protectors and Locks for Bags or Satchels, of which the following is a specification, reference being had therein to the accompanying drawings.

This invention relates to new and useful improvements in combined corner-protectors and locks for bags or satchels; and the invention consists in the peculiar construction, arrangement, and combination of the different parts, as hereinafter described, and set forth in the claims.

In the drawings which accompany this specification, Figure 1 is a vertical central longitudinal section through the corner of the satchel-bow having my device secured to it. Fig. 2 is a perspective view of the device detached from the satchel, which is arranged for the reception of the device. Fig. 3 is another vertical central longitudinal section through the device detached, and with the locking-lever latch thrown open. Fig. 4 is a top plan, and Fig. 5 is a bottom plan, with the latch closed in both figures.

A and B are the two co operating bows of the satchel, to the rounding corner of the outer one of which my device is intended to be attached for the purpose of preventing the satchel from spreading open by the pressure 35 of the contents, and at the same time form a protection to prevent wearing or tearing of the material with which in the more highly-finished articles of this kind the bows are covered. This protection is provided by the curved plate C, which is of corresponding shape and size with the corner of the bow to make a fit thereon, being secured thereto by rivets placed through the ends of the plate; and to give a finished appearance to the plate 45 C, I bevel the sides and ends and give it a finish on the exposed side. In one end of this piece is formed the recess D, within which is concealed the plate E, so as to give the appearance of a complementary portion of the plate itself, with the exception that a little recess is left at one end for the insertion of a

finger-nail to raise the plate E in the operation of the device, as hereinafter described. This plate E forms one part of a locking lever or latch, and is fulcrumed by means of the rivet F passing laterally through the plate. The other arm of this locking lever or latch projects below the plate, and has an angular bend, which brings the free end J parallel, or nearly so, to the plate. This arm of the lever 60 works through a slot, G, provided in the bow of the satchel, to which the plate is secured. The locking-lever, being thus constructed, is held in a normally-closed position, as shown in Figs. 1 and 4, by means of a spring, H, 65 which is secured to the under side of the plate and engages with its free end into a V-shaped recess formed on the locking-lever near the fulcrum, so arranged that the locking-lever will find a position of rest when in an open position, (shown in Fig. 3,) but will immediately snap to a closed position when slightly moved toward its closed position.

I is a beveled catch secured to the corner of the opposite bow B, coincident with the free end J of the locking-lever.

In practice, the parts being constructed and arranged as described, it will be seen that the latch is self-closing—that is, if the satchel is open, the bows have to be nearly pressed together to have the catch engage with the free end of the locking-lever, and to still further aid this operation the part J is also beveled off on the same plane as the catch. By having the outer arm or plate, E, confined upon its sides 85 by the walls of the recess D the lever is less liable to be accidentally opened, and the corner-plate C is strengthened thereby, and as the nail-hole for lifting it is at the lower end it is entirely concealed from view, and the secret of the lock is not easily detected by any uninitiated person, and thereby affords additional protection.

If preferred, the nail-hole may be brought down still farther to the end of the plate C, so as to be still more concealed.

What I claim as my invention is—

1. The combination, with a curved corner-protector, C, having the recess D formed therein, a self-acting locking-lever pivotally secured within that plate C, and consisting of the plate or arm E, adapted to form a comple-

mentary part of the plate C, the inwardly angularly-bent projecting arm J, and the spring H, secured to the plate C and engaging in the V-shaped recess of the locking-lever, all arranged substantially as and for the purpose described.

2. In the combined corner-protector and lock for bags and satchels, the combination of a curved corner-plate secured to the outer bow, 10 a locking-lever pivotally secured in a recess therein, and consisting of an outer arm or plate adapted to engage in a recess of the corner-plate and form a complementary part thereof,

an inwardly-projecting arm terminating in an angular bend, and parallel, or nearly so, to the corner-plate, and provided with a bevel, and a catch secured to the inner bow and having an inclined bevel, substantially as and for the purpose described. 15

In testimony whereof I affix my signature, 20 in presence of two witnesses, this 29th day of July, 1887.

ALBERT PETERSON.
